DRIVING MECHANISM AND AUTOMATIC
STOP MEANS THEREFOR

George J. Uhlig, Chicago, Ill., assignor to Victor
Adding Machine Company, Chicago, Ill., a cor-
poration of Delaware

Original application December 30, 1933, Serial No.
704,648. Divided and this application July 2,
1934, Serial No. 733,449

14 Claims. (Cl. 192—149)

This invention relates to improvements in driving mechanism and automatic stop means therefor which is more particularly adapted for controlling the connections of machines with their 5 source of power, and is a division of my pending application, Serial No. 704,648, filed December 30, 1933.

The device is illustrated as being attached to an adding machine in which a single revolution 10 or cycle is required for its normal operation to set up the parts and position the type bars for making an impression thereof and for restoring them to their normal positions during the cycle. Provision is also made whereby a number of successive cycles may be had at the will of the operator.

The chief objects of the invention are the provision of mechanism adapted to be engaged and driven for a complete cycle under the driving 20 power of a motor and to be automatically disengaged and brought to rest in a predetermined position upon the completion of the cycle.

Another object is the provision of a finger bar which is manipulated by the operator in starting 25 the operation of the machine and which has connections cooperating with the driving mechanism for effecting and for automatically releasing the driving connection upon the completion of the cycle. The invention is capable of being 30 employed with particular advantage in connection with a constantly running motor, since the driving mechanism is controlled for engagement by means of the finger bar and is automatically disengaged upon the completion of the cycle.

Still another object is the provision of yieldable 35 means between the driving and the driven parts for cushioning the shock at the start of the operating stroke and at the completion of the cycle when the mechanism is disengaged.

In the accompanying drawings embodying my 40 invention, I show the device as being attached to an adding machine, but do not wish to be limited to the operation and action solely to an attachment while all of the features embodied 45 in these improvements will be substantially the same.

Figure 1 is a side elevation illustrating my 50 device as attached to an adding machine with the casing thereof in cross-section and the control parts extending from the device to operate the machine.

Figure 2 is an enlarged detail cross-sectional 55 view taken substantially on the lines 2—2 of Figs. 1 and 3.

Figure 3 is an enlarged longitudinal sectional

view of the clutching mechanism with parts thereof being shown partially in elevation.

The mechanism includes a housing 15 provided with a plurality of ears 16 for attaching and supporting the device in position on a frame 17 which is secured to the bottom wall 18 of the adding machine. The housing 15 is provided with a horizontally extending portion 15a for housing a motor 19 which has a shaft 20 journaled in a bearing 21 supported on a wall 22 disposed between the housings 15 and 15a. The shaft 20 of the motor 19 is provided with a transverse tongue portion 23 which fits into a transverse slot opening 24 milled in one end of a worm 25 and axially aligned therewith to be driven 15 by the motor 19. The worm 25 has its other end portion journaled in an adjustable bearing 26 carried in the outer wall of the housing 15 which serves as an end-thrust bearing for taking the driving thrust of the worm 25 while 20 driving a worm-wheel 27 carried in the housing 15 for driving the mechanism. The worm-wheel 27 is in the form of a ring-gear being provided with a central bore 28 and is supported for turning movements with and independently of a 25 shaft 29 that extends therethrough and is mounted thereon by means of a collar 30 freely carried on the shaft 29 by means of a disc 32. The disc 32 is fixed to one end of the collar 30 and has the studs 33 and 34 fixed thereto in diametri- 30 cally opposed relation with their free ends extending through openings 35 and 36 respectively in the worm-wheel 27 for supporting the same concentrically on the shaft 29. Each of the studs 33 and 34 are provided with the shoulder 33a and 35 34a respectively adjacent the disc 32 for supporting the worm-wheel 27 in spaced relation therewith. The shoulder 33a of the stud 33 provides for the attachment of the leg 37 of a torsion 40 spring 38 which has its body portion encircling the collar 30 and disposed within the bore 28 of the worm-wheel 27 and with the other leg 39 of the torsion spring 38 fixed to a stud 40 on a lever member 41 which is fixed to a collar 42 carried in fixed relation for turning movements with 45 the shaft 29 by means of a pin 43.

The stud 34 is relatively longer than the stud 33 and extends into the path of the lever member 41 which is normally urged against the stud 34 by means of its connection with the torsion 50 spring 38 secured thereto.

With this construction, the torsion spring 38 will permit of a flexible drive between the worm 25 and the driven shaft 29, and to relieve the driving strain on the torsion spring 38, I pro- 55

vide a drum 44 which is carried on the worm-wheel 27 and driven therewith by means of the studs 33 and 34 extending through the openings 46 and 47 respectively in the drum 44. A band 5 48 extends within the drum 44 and yieldingly engages the inner periphery thereof by means of the compression spring 53 interposed between the inturned ends 49 and 50 and guided on the reduced portions 51 and 52 thereof. The band 10 48 is provided with cut-away portions 54 and 55 respectively on one edge thereof to receive the opposite ends 41a and 41b of the lever member 41 therein for turning movements therewith.

During the turning movements of the worm 15 25, the worm-wheel 27 will be driven thereby and the drum 44 fixed thereto will frictionally drive the band 48 and carry the lever 41 therewith by means of its connection with the band at 54 and 55 and the arm 41 will also be driven 20 by means of the leg 39 of the torsion spring 38 being fixed thereto and with its other leg 37 carried with the worm-wheel 27. The above constitutes the flexible driving mechanism for the driven shaft 29 that has means thereon for 25 engaging the driving mechanism and which is connected to the parts of the machine to be driven.

The arm 41 carries a toothed wheel 236 in spaced relation therewith on spacing studs 237 30 and is adapted to be intermittently engaged to drive the machine. A crescent-shaped arm 228 having an inwardly turned extension 234 which is adapted to normally overlie the teeth 235 of the wheel 236 and is pivotally mounted on a pin 35 230 carried on a member 231 with its free end portion provided with an outwardly extending pin 226 that extends through a slot opening 227 in the member 231 for limiting its movements thereon. The arm 228 is normally urged in one 40 direction by means of a tension spring 233 connected to the free end thereof and to an ear 231a of the member 231 which tends to draw the arm 228 to cause the extension 234 thereof to engage the teeth 235 of the wheel 236 as this 45 extension 234 is normally retained out of engagement with the teeth 235 by means of the pin 226 engaging a stop-arm 225 that extends into its path of travel.

The member 231 is fixed to a collar 232 which 50 is secured to a sleeve 238 that surrounds the reduced end 229 of the shaft 29 and extends outwardly through a cover-plate 258 and is journaled in the bearing 239 therein. A speed control cam 256 is secured to the free end of the 55 bushing 238 and is turnable as a unit with the member 231 so that as the crescent-shaped arm 228 carried thereon is released and the extension 234 thereof engages the teeth 235 of the wheel 236, the member 231 and the speed control 60 cam 256 will be driven as a unit with the driving mechanism under the driving action of the worm-wheel 27 and the worm 25, and by reason of the cam 256 being connected to the operating parts of the machine, a driving action thereof 65 will be had.

A link 200 is pivotally connected to the cam 256 by means of a pin 299 and at its other end is pivotally connected with a lever 102 fixed to the actuator shaft 103 of the machine so that a 70 rotary movement of the cam 256 will cause a rocking movement of the lever 102 to rock the actuator shaft 103 for the operating movement of the machine.

To actuate the device, I provide a finger bar 75 123 carried for vertical sliding movements on the

casing of the machine and which has a frame 123a provided with a slot opening 137 at its lower-most end portion through which a pin 138 extends being fixed to the casing of the adding machine to guide and limit the movement in either direction of the finger bar 123. The lower end of the finger bar frame 123a normally rests against a pin 139 fixed to an arm 140 which is fixed for rocking movements with the arm 240 which is pivotally connected to a link 220 by 10 means of a pin 221 and has its other end connected by means of a pin 222 to an arm 223 secured to a stud shaft 224 to which the stop arm 225 is secured. The link 220 extends beyond the arm 223 and is pivotally connected to a contact 15 lever 255 which carries an insulated roller 257 adapted to engage a leg 191 of a contact switch 192 that is connected to the motor 19 and has the leads 94 and 96 connecting the same to a source 20 of power supply.

Upon depressing the finger bar 123, the lower end of the frame 123a thereof will engage the pin 139 and cause a rocking movement of the arms 140 and 240 and exert a pull on the link 220 and cause a rocking movement of the arm 223 and the stud shaft 224 to carry the stop-arm 225 out of the path of the pin 226 fixed to the crescent-shaped arm 228 and permit the same to be drawn by means of the tension spring 233 until the extension 234 thereof engages the teeth 30 235 of the wheel 236. The pulling action of the link 220 will cause the contact lever 255 to rock and the roller 257 carried thereon to engage the leg 191 of the contact switch 192 and close the circuit to energize the motor 19 and drive the 35 worm 25 and the worm-wheel 27. The driving movement of the worm-wheel 27 will carry the toothed-wheel 236 therewith by reason of its connection with the torsion spring 38 which is also connected to the lever member 41 that carries 40 the toothed-wheel 236 and when engaged by the extension 234 of the crescent-shaped arm 228 will drive the speed control cam 256 to drive the machine. The speed control cam 256 is provided with a cam portion 256a that engages a roller 45 205 carried on a pin 204 which is secured to a rocker arm 206 mounted on a pin 255a and which has an overhanging extension 207 adapted to engage the roller 257. The rocker arm 206 has a tension spring 272 connected thereto and to 50 the bottom wall 18 of the machine for urging the roller 205 in engagement with the periphery of the disc 256 and as the cam portion 256a thereof is moved in advance of the roller 205, this tension spring 272 will cause a rocking movement 55 of the rocker arm 206 until the extension 207 thereof engages the roller 257 for retaining the leg 191 of the contact switch 192 in closed position.

The link 220 is operatively connected to the 60 contact lever 255 by means of a slot opening 220a having a guide block 220b slidably mounted therein and pivotally attached to an arm 255b of the contact lever 255. This slot opening 220a permits of a sliding action of the link 220 with 65 respect to the contact lever 255 so that upon its restoring movement no action will be had on the contact lever 255 and the roller 257 thereof will be retained in contact with the leg 191 of the contact switch 192 by means of the arm 206 under the influence of the tension spring 272 and the arm 255b will be moved only when the cam portion 256a of the cam 256 has passed over and beyond the roller 205 of the arm 206 (Fig. 1). At this time the arm 206 will be rocked 75

against the spring 272 and cause the extension 207 to be raised out of contact with the roller 257 and the spring tension in the leg 191 of the contact switch 192 will cause the contact lever 5 255 to rock on the pivot pin 255a and permit of its movement in the slot opening 220a of the link 220.

As the finger bar 123 is released, a tension spring 241 fixed to the arm 240 and to the frame 17 will exert a tension on the link 220 and restore the arm 223 and the stop-arm 225 and will also cause a movement of the link so that the opening 220a thereof will freely permit the link to slide to relieve the pulling strain on the contact lever 255. As the rise of cam portion 256a of the disc 256 has passed the roller 205 of the arm 206 the extension 207 thereof will be moved free of the roller 257 and permit the leg 191 of the contact switch 192 to spring to open position 20 to open the circuit.

The link 220 is connected to the arm 223 and to the contact lever 255 so that the movement of the link 220 under the control of the finger bar 123 controls the disengagement of the stop-arm 225 and the engagement of the leg 191 to close the circuit in the contact switch 192 to the source of supply.

A constantly running motor may be used with a driving mechanism of this type and when used, 30 the contact lever 255 and roller 257 carried thereon may be omitted, as a manually actuated contact switch will serve the purpose for closing the circuit to start the motor.

It will be noted, that with the construction 35 shown in the drawings, the depression of the finger bar 123 simultaneously removes the stop-arm 225 from abutting engagement with the pin 226 of the crescent-shaped arm 228 and closes the circuit by causing the movement of the contact lever 255 to cause the roller 257 thereof to 40 depress the leg 191 and close the contact switch 192 from the main source of supply to the motor 19. When a constantly running motor is used, the link 220 operatively connected to the finger bar 123 and to the arm 223 does not extend to 45 the contact lever 255 as the contact switch is then arranged for manual manipulation independently of the finger bar 123. The arm 206 however, remains in position with its roller 205 50 engaging the periphery of the speed control cam 256 under the tension of the spring 272 which in either case serves to assist the turning movement of the cam 256 at the start of its movement as the stopping position is about half way 55 of the fall of the cam portion 256a and as the stop arm 225 is moved out of engagement with the pin 226, the spring 272 which is constantly urging the roller 205 against the fall of the cam portion 256a will cause a starting movement of 60 the speed control cam which will be carried for a full cycle under the driving force of the motor 19.

As the stop arm 225 is released from the pin 65 226, the extension 234 of the crescent-shaped arm 228 will engage the teeth 235 of the wheel 236 and should this wheel 236 be in driving relation with the motor 19, a cushioning effect will be had therebetween to absorb the starting shock by means of the torsion spring 38 interposed between the worm-wheel 27 and the toothed-wheel 70 236. The band 48 which is normally in contact with the drum 44 carried with the worm-wheel 27 adds a frictional tension to the turning movements of the lever member 41 and the toothed- 75

wheel 236 carried thereon as the extension 234 is released for engagement therewith.

I contemplate as being included in these improvements all such changes, variations and departures from what is thus specifically illustrated 5 and described as fall within the scope of the appended claims.

I claim:—

1. A device of the character described, comprising in combination, a driven shaft, an electric motor for driving the driven shaft, engageable means including a resilient connection between the motor and the driven shaft, clutch means coacting with said resilient driving means, means coacting with said clutch means normally 15 urging the same to engage said engageable means, stop means coacting with the clutch means disengaging the same from the engageable means, and manually controlled means for releasing said stop means to effect the engagement of the clutch 20 means with the resilient driving means and the turning movements thereof with the driven shaft.

2. A device of the character described, comprising in combination, a driven shaft, an electric motor for driving the driven shaft, resilient 25 means including frictional means having a driving connection with the motor, clutch means coacting with said resilient means and frictional means, said clutch means being adapted to intermittently engage said resilient and frictional 30 means to drive the driven shaft, and means in the path of movement of and coacting with the clutch means for disengaging the same from the driving means in timed relation with a revolution of the device. 35

3. A device of the character described, comprising in combination, a driven shaft, an electric motor for driving the driven shaft, engageable means including a resilient connection between the motor and the driven shaft, clutch means 40 coacting with said engageable means for driving mechanism outwardly thereof, said clutch means being adapted to intermittently engage said engageable means, manually controlled means, stop means under the control of the manually 45 controlled means and coacting with the clutch means retaining the clutch means disengaged from the engageable means, and means whereby the clutch means is engaged with the engageable means when the manually controlled means is 50 operated and held engaged during a complete cycle of operations.

4. A device of the character described, comprising in combination, driven engageable means, an electric motor including connections for driving 55 the engageable means, a circuit for the motor including a switch normally retaining the circuit open, said engageable means adapted to be driven with the motor as the switch is closed in the circuit, engaging means coacting with the engageable means, manually manipulative means having connections with the switch and the engaging means for simultaneously closing the switch in the circuit and enabling the connection of the engaging means with the engageable 65 means and means under the control of the manually manipulative means whereby the switch will be moved to open the circuit and the engaging means will be disconnected from the engageable means upon the completion of a cycle of said engageable means. 70

5. A device of the character described, comprising in combination, a main driven shaft, an electric motor for driving the driven shaft, engageable means including a resilient connection 75

- between the motor and the driven shaft, a circuit for the motor including a switch normally retaining the circuit open, the said engageable means being adapted to be intermittently connected to the parts to be driven and permanently connected with the motor, clutch means coacting with said engageable means for driving the mechanism outwardly thereof, and manually controlled means having connections with the switch and the clutch means for simultaneously closing the circuit to the motor and to cause engagement of the clutch means with the engageable means, stop means in the path of travel of the clutch means causing the disengagement thereof with said engageable means, and means whereby said switch is opened in the circuit in timed relation with a revolution of the device.
6. A device of the character described, comprising in combination, driven engageable means, an electric motor including a yieldable connection for driving the engageable means, a circuit for the motor including a switch normally open in the circuit, the said engageable means being adapted to be driven with the motor as the switch is closed in the circuit, manually controlled means adapted to close the said switch providing a driving connection between the motor and the driven shaft, and clutch means coacting with the engageable means to be driven thereby, and means under the control of the manually controlled means whereby said switch will be moved to open the circuit and the clutch means will be disengaged from the engageable means upon the completion of a cycle of said engageable means.
7. In combination, a machine, a motor for driving said machine, resilient means including engaging means forming a driving connection between said motor and said machine, means actuated by a common control for connecting said engaging means with the resilient means and for connecting said motor with a source of power to drive the resilient means with the engaging means whereby upon the completion of a cycle said motor will be disconnected from the source of power and said engaging means will be automatically disengaged from said resilient means.
8. A device of the character described, comprising in combination, a main driven shaft, an electric motor for driving the driven shaft, a circuit for the motor including a switch normally retaining the circuit open, the said driven shaft adapted to be permanently connected to the motor and intermittently connected to parts to be driven, stop means in the path of the turning movements of the driven shaft disabling the connection of the parts therewith, and manually controlled means adapted to close the switch providing a driving connection between the motor and the driven shaft and to effect the release of said stop means for enabling the connection of the parts for a cycle of operations with the driven shaft.
9. A device of the character described, comprising in combination, a main driven shaft, an electric motor for driving the driven shaft, a circuit for the motor including a switch normally open in the circuit, mechanism adapted to be driven by the main driven shaft and intermittently connected to parts to be driven, means actuated by a common control for closing the switch to the motor and for connecting the mechanism with the main driven shaft, and means coacting with the turning movements of the mechanism

and under the control of said common control whereby said mechanism is disengaged from the driven shaft at the completion of a cycle of said driven shaft.

10. A device of the character described, comprising in combination, a driven shaft, an electric motor for driving the driven shaft, a circuit for the motor including a switch normally open in the circuit, the said driven shaft being adapted to be permanently connected to the motor and intermittently connected to parts to be driven, and manually controlled means adapted to close the said switch providing a driving connection between the motor and the driven shaft and to connect said driven shaft to parts to be driven whereby said switch is opened in the circuit and the parts driven are released in timed relation with a revolution of the device.

11. A device of the character described, comprising in combination, a driven shaft, an electric motor for driving the driven shaft, engageable means including a resilient connection between the motor and the driven shaft, means coacting with said engageable means for driving mechanism outwardly of the device, said last named means being adapted to intermittently engage said resilient driving means, stop means coacting with the last named means for disengaging the same from the engageable means, the said resilient connection permitting of a differential movement of the engageable means with the motor for absorbing the connecting and disconnecting shock to the device.

12. A device of the character described in combination with a machine having a cycle of operations, an electric motor for driving said machine, a source of power connected to said motor, resilient means including a clutch for forming a driving connection between said motor and said machine, said clutch comprising a toothed wheel carried with the resilient means, an oscillating member carried for engagement with the toothed wheel to drive the machine, and means for automatically disconnecting the oscillating member from the toothed wheel upon the completion of each cycle of operations.

13. In combination, a machine, a motor for driving said machine, resilient means including frictional means forming a driving connection between the motor and the machine, clutch means coacting with the resilient means, means including a manually manipulative member for actuating said clutch and for connecting the motor with a source of power, and means in the path of said clutch and under the control of the manually manipulative member for disconnecting the same upon the completion of a cycle of operations.

14. In combination, a machine, a motor for driving said machine, resilient means including frictional means forming a driving connection between said motor and said machine, clutch means coacting with the resilient means, means actuated by a common control for connecting said clutch means with the resilient means and for connecting said motor with a source of power to drive the resilient means with the clutch means whereby upon the completion of a cycle said motor will be disconnected from the source of power and said clutch means will be disengaged from the resilient means, said frictional means frictionally resisting the resilient means during the engagement and disengagement of the clutch means therewith.
